CARBURETER OR THE LIKE.

1,089,516.

Specification of Letters Patent.

Patented Mar. 10, 1914.

Application filed June 12, 1911. Serial No. 632,588.

To all whom it may concern:

Be it known that I, WALTER C. WESTAWAY, a citizen of the United States, residing at Belvidere, in the county of Boone and 5 State of Illinois, have invented certain new and useful Improvements in Carbureters or the like, of which the following is a description.

My invention belongs to that general class 10 of devices known as carbureters, designed to suitably and efficiently co-mingle fluids, as for example air and a suitable hydro-carbon, and has among its objects the production of a simple, efficient, durable and satisfactory device of the kind described for use 15 wherever found applicable.

To this end my invention consists in the novel construction, arrangement and combination of parts herein shown and described, 20 and more particularly pointed out in the claims.

In the drawings, wherein like reference characters indicate like or corresponding parts, Figure 1 is a sectional view of my device taken substantially on line 1, 1 of 25 Fig. 2. Fig. 2 is a sectional view taken substantially on line 2, 2 of Fig. 1. Fig. 3 is a perspective view of the valve member 49. Fig. 4 is a sectional view taken substantially 30 on line 4, 4 of Fig. 1. Fig. 5 is a sectional view taken substantially on line 5—5 of Fig. 1. Fig. 6 is a sectional view taken substantially on line 6, 6 of Fig. 1. Fig. 7 is a side elevation of the upper portion of 35 my device, looking substantially from the line 7, 7 of Fig. 2. Fig. 8 is a sectional view of the valve member, and Fig. 9 is a sectional view of the same, taken substantially on line 9, 9 of Fig. 8.

Referring to the drawings, in which my preferred form of device is shown, the casing 40 comprises a shell 1—2 provided with a suitable base 5 and top 12, the same being secured thereto in any suitable manner. Any 45 suitable arrangement for securing the parts together may be employed. As shown, the base is secured to the top by a coupling 4, which engages the base, and a suitable extension on the casing part 1. The base may 50 be of any suitable form, as shown it is provided with a plurality of outlets for connection with an engine having a plurality of

cylinders. Referring particularly to Fig. 1, the base is extended in the form of a pipe 6 provided with outlets 8, the interior of the 55 pipe being connected or open to the interior of the casing by an opening 7, so that the mixture may pass through the opening to the outlets 8 through suitable pipes to the engine. Where the device is used on a single cylinder engine, one of the outlets 8 may be closed, or the base may be made with only one outlet. This, however, is a matter of detail, as the base may be formed with any desired number of outlets. The top 12 is 60 provided with one or more openings 13 for the admission of air or the like, and with a suitable hydro-carbon or fluid inlet, as will be more fully explained in the operation of the device. 70

Arranged within the casing is a member which preferably comprises shells 15 and 16 separated by a partition 20. The partition 20 is arranged to serve as a valve within the casing, the same being provided with 75 a face 17 arranged to cooperate with a suitable valve seat 11 within the casing. The shells 15 and 16 are preferably flanged on the exterior as at 18 and 19, so as to contact with the inner walls of the casing at those 80 points, chambers 27 and 33 being formed between the shells 15 and 16 and the casing. The shell 15 is provided with a plurality of openings 22 therein, the same being preferably in the form of narrow slots, and the 85 part 16 on the opposite side of the partition is also provided with a plurality of similar openings 23, it being understood that the arrangement of the openings may be such as desired. It will be seen that the preferred 90 construction comprises a valve member provided with a tubular extension on each side thereof, each extension being provided with openings therethrough. The partition or valve 20 is preferably extended as at 24 and 95 21 (see Fig. 8) and provided with an opening 25 therethrough, through which is arranged a valve stem 28 that controls the admission of oil or hydro-carbon to the casing, as hereafter described. The valve is 100 normally maintained upon its seat 11 by a resilient member 26, or its equivalent, which bears against the base 5 and against the lower side of the partition or valve 20, the

2

resilient member being maintained against displacement by the extended rim or ring 24 upon the under side of the valve, and a suitable recess in the base (see Fig. 1).

5 As is most clearly shown in Fig. 1, 28 is a valve stem provided with a needle valve end 32, which controls the admission of oil to the interior of the device through a duct 35. The stem 28 is resiliently maintained 10 against its seat 34 (see Fig. 5) by a resilient member 31, or its equivalent, 30 being a baffle arranged on the valve stem, and 29 a nut or its equivalent for maintaining the valve in position and limiting its movement.

15 The duct 35 extends to the face of the top 14, and the oil or hydro-carbon may be admitted thereto and the supply controlled in any desired or preferred manner. As shown, I extend the top 14, as shown at 38, 20 the top being provided with a duct 36 and 37 from the face 44 of the top to the exterior. At the end of the part 38 I show a cap 41 and part 39, 42 being suitable packing material. The fuel or oil supply pipe is 25 connected to the extension 38, so the oil passes through the duct 42 and ducts 37 and 36 to the face 44. The admission of oil, however, is controlled by a suitable valve 49, or its equivalent, preferably arranged to 30 seat upon the face 44. The valve 49 is provided with a slot or groove 50 therein, which is preferably at an angle, or has one face or side angling, so that as the same is moved or upon the face 44, it gradually opens or 35 closes the duct 35 and controls the flow of fluid therethrough. The valve 49 may be controlled and maintained upon its seat in any suitable manner. As shown, it is arranged within a casing 45, secured upon the 40 face 14 of the top 12 by screws 46, or their equivalents, the casing 45 being provided with a chamber 47 therein, in which the valve is arranged, the casing being arranged to guide the valve in its movement. The 45 valve is maintained tightly upon its seat or the face 44 by a part 51, which is maintained in close contact therewith by a resilient member 52, or its equivalent, arranged in the extended part 53 of the valve casing 45.

50 A simple construction for operating the valve comprises a lever 56 above the mounted or the extended part 58 of the casing, and provided with teeth 57, arranged to mesh with teeth 55 on the valve, so that as 55 the lever 56 is turned about its pivot, the valve member 49 is moved longitudinally in the desired direction.

Any suitable means may be employed for controlling the admission of air to the interior of the casing. As shown, a very simple construction is a plate 61 arranged upon the end or top of the part 2, and provided with openings 62 therethrough (see Fig. 1). Any suitable means may be employed for maintaining the plate against ro-

tation, as for example, a pin 60 (see Fig. 1) is provided for the purpose. The top 12 is preferably extended as at 63 to the lower side of the plate 61. Arranged above the plate 61 is a plate 64, provided with openings 65 therethrough (see Fig. 4) the openings shown being of such size as to register with the openings 62 when the top plate 64 is moved to its extreme position. The plate 64 is arranged to be moved so that when rotated about the extended part 63, the openings 62 and 65 will not register exactly, so that the openings for the air may be diminished as desired. Any suitable means may be employed for operating the plate 64, or maintaining the same in the desired position. As shown, the plate 64 is extended through one of the air inlets 13, as at 66, and provided with a pin 68 and a resilient member 69, the pin 68 being adapted to engage suitable notches 71 in the top part, normally maintaining the plate 64 against the movement. As shown, the pin 68 is provided with a knob 70 for convenience in operating, and the part 66 is extended as at 67, and may be in the form of a pointer arranged to coöperate with suitable graduations 72, to indicate the position of the plate.

Any suitable means may be employed for opening the valve 15—16, if it is desired to prime the carburetor. As shown, a pin 74 is provided, which extends through the top 12 to the flange 19, and is resiliently maintained up by a spring 76, a collar 75 being provided for limiting its movement. At the end of the pin 74 is a top 77 for convenience in operating.

The operation of the device may be briefly described as follows: Assuming that the carburetor is suitably connected to the fuel supply pipe and to the engine, the valves being substantially in the position shown. At each impulse of the engine in drawing in a fresh charge, the valve 20 and extensions 15, 16 are drawn downward, thereby drawing down the valve 32 and permitting the oil to enter the interior of the casing, the air being drawn in through the openings 13, 65 and 62. The oil or hydro-carbon is conducted to the duct 35, controlled by the valve 32, through the ducts 40, 37 and 36 and chamber 50 in the valve 49. The oil drops upon the baffle or deflector 30, where it is met by the air and the oil and air passing through the openings 23 into the chamber 33, and as the valve is open, by the valve seat 11 between the valve face 17 and the seat and into the chamber 27, thence through the openings 22 to the interior of the shell 125 or tubular extension 15 through the outlet 7 and outlets 8 to the engine cylinders. As soon as the charge is admitted the resilient member 26 shuts the valve 20, thereby shutting the valve 32, preventing the oil from 130

entering the casing through the duct 35. The amount of oil admitted may be increased or decreased by operating the lever or throttle 56, thereby exposing more or less of the duct 35 for the admission of oil. The air may be controlled by shifting the position of the end 64. As the oil and air strike the baffle 30 and pass through the openings 23, they are co-mingled and are further co-

mingled as they pass between the valve face 17 and its seat 11, and are further co-mingled in passing through the openings 22, so that when they reach the outlet 7 they are properly co-mingled to give a perfect mixture.

As is obvious, when the engine is not running the valve 20 is positioned upon its seat 11 and the duct 35 is closed by the valve 32, so that the carbureter is not flooded. If it is necessary to prime the carbureter, the button 77 may be depressed, thereby operating the pin 74, which pin resting upon the flange or top 19 of the shell 16, depresses the valve 20 and thereby opens the valve 32, so that the hydro carbon or oil is admitted to the carbureter.

Having thus described my invention, it is obvious that various immaterial modifications may be made in the same without departing from the spirit of my invention, hence I do not wish to be understood as limiting myself to the exact form, construction or combination of parts herein shown and described, or uses mentioned.

What I claim as new and desire to secure by Letters Patent is:—

1. In a carbureter, the combination of a vertically disposed casing having intermediate its ends an interior annular shoulder forming a valve seat, a valve disk to engage said seat, vertically extending tubular parts projecting in opposite directions from said disk, and each having an open end with an outer annular flange to engage the inner surface of the casing, the wall of each tubular part between each flange and the valve disk being spaced throughout from the wall of the casing, and each having a series of circumferentially extending relatively narrow elongated openings, said openings being relatively small and closely associated from top to bottom and therearound.

2. In a carbureter, the combination of a vertically disposed casing having intermediate its ends an interior annular shoulder forming a seat, a valve disk to engage said seat, vertically extending tubular parts projecting in opposite directions from said disk, and each of said tubular parts having an outer open end with a surrounding annular flange to engage the inner surface of the casing, the wall of each tubular part between said flange and the valve disk being spaced from the wall of the casing, and each of the tubular parts having a series of openings,

said openings being relatively small and closely associated throughout the length of said wall, a plurality of valve controlled inlets leading from the casing to the open end of the upper tubular part, and a spring positioned within the lower tubular part adapted to engage at one end the valve disk and at its opposite end a part of said casing.

3. In a carbureter, a vertically arranged casing open at opposite ends, the lower portion of the casing being enlarged relative to the upper portion thereof to form an annular valve seat intermediate its ends, a tubular valve member arranged in said casing, the lower portion thereof being enlarged relative to the upper portion thereof to form an annular valve disk intermediate its ends to engage said seat, the tubular member having a central partition dividing the same into two parts, the annular wall of each of which is spaced from the casing and has a plurality of relatively small openings throughout.

4. In a carbureter, a vertically arranged casing open at opposite ends, the lower portion of the casing being enlarged relative to the upper portion thereof to form an annular valve seat intermediate its ends, a tubular valve member arranged in said casing, the lower portion thereof being enlarged relative to the upper portion thereof to form an annular valve disk intermediate its ends to engage said seat, the tubular member having a central partition dividing the same into two parts, the annular wall of each of which is spaced from the casing and has a plurality of relatively small openings throughout, and valve controlled means at the upper open end of the casing for admitting fluid into the interior of the upper part of the tubular member.

5. In a carbureter, a casing provided with an inlet and outlet and with a valve seat therebetween, a valve member arranged in said casing, comprising a tubular part provided with a partition between its ends and with a face substantially proximate said partition arranged to seat on said casing seat, said part provided with a plurality of closely associated relatively small openings therethrough on each side of said partition and substantially throughout the length of said parts.

6. In a carbureter, a vertically arranged casing open at opposite ends, the lower portion of the casing being enlarged relative to the upper portion thereof to form an annular valve seat intermediate its ends, a tubular valve member arranged in said casing, the lower portion thereof being enlarged relative to the upper portion thereof to form an annular valve disk intermediate its ends to engage said seat, the tubular member having a central partition dividing the same into two parts, the annular wall of each of

- which is spaced from the casing and has a plurality of relatively small openings throughout, valve controlled means at the upper open end of the casing for admitting fluid into the interior of the upper part of the tubular member, and a spring interposed between the under surface of the partition and lower end of the casing to normally hold said valve disk on its seat.
7. In a carbureter, the combination of a vertically arranged casing open at its opposite ends, the lower portion of the casing being enlarged relatively to the upper portion thereof to form an annular valve seat intermediate its ends, a tubular valve member arranged in said casing, the lower portion thereof being enlarged relative to the upper portion thereof to form an annular valve disk intermediate its ends to engage said seat, the tubular member having a central partition dividing the same into two parts, the annular wall of each of which is spaced from the casing and has a plurality of vertically spaced series of circumferentially extending narrow slots.
8. In a carbureter, the combination of a vertically arranged casing open at its opposite ends, the lower portion of the casing being enlarged relatively to the upper portion thereof to form an annular valve seat intermediate its ends, a tubular valve member arranged in said casing, the lower portion thereof being enlarged relative to the upper portion thereof to form an annular valve disk intermediate its ends to engage said seat, the tubular member having a central partition dividing the same into two parts, the annular wall of each of which is spaced from the casing and has a terminal flange to engage said casing thereby forming a chamber between said flange and valve disk, and each of the tubular extensions having throughout the length thereof a series of closely associated openings.
9. In a carbureter, the combination of a vertically arranged casing open at its opposite ends, the lower portion of the casing being enlarged relatively to the upper portion thereof to form an annular valve seat intermediate its ends, a tubular valve member arranged in said casing, the lower portion thereof being enlarged relative to the upper portion thereof to form an annular valve disk intermediate its ends to engage said seat, the tubular member having a central partition dividing the same into two parts, the annular wall of each of which is spaced from the casing and has a terminal flange to engage said casing thereby forming a chamber between said flange and valve disk, each of the tubular extensions having throughout the length thereof a series of closely associated openings, a valve positioned on the upper flanged end of the tubular member for controlling the inlet of air,

and auxiliary means for controlling the admission of fluid into the open upper end of the tubular member.

10. A valve construction for carbureters, comprising a casing having closed side walls and open ends forming an inlet and an outlet, a valve disk arranged to engage an annular seat intermediate the ends of the casing, tubular walls projecting from opposite sides of the disk and spaced from the side wall of the casing to form annular chambers, each of said tubular walls being open at its outer end to communicate one with the inlet and the other with the outlet, and the tubular walls being provided with closely associated openings therethrough, said side walls being further provided each with an annular flange at their open ends to engage the side walls of the casing, and a disk shaped valve positioned upon one of said flanges and adapted to control the adjacent end of the opening of the tubular wall.

11. A carbureter comprising a vertically disposed casing having an annular valve seat on its inner wall spaced from the upper end thereof, a vertically movable disk shaped valve part adapted to engage said seat, a tubular wall projecting upwardly from the disk member and spaced from the side wall of the casing, said tubular wall having at its upper end an annular flange engaging the inner wall of the casing, and forming between the flange and disk an annular chamber, said tubular wall also having a plurality of series of closely associated relatively small openings leading from the interior of the tubular wall to said annular chamber, and valve controlled means for introducing material to be mixed into the inner chamber of the tubular wall through the open upper end thereof.

12. In a carbureter, the combination of a vertically disposed tubular casing having intermediate its ends an internal flange, a vertically movable valve positioned in the casing, the valve comprising a horizontally disposed disk adapted to seat upon said flange in its upward movement, a spring interposed between said disk and a stationary part of the casing, for normally holding the disk in engagement with the flange, oppositely disposed tubular extensions on the disk, said extensions being spaced from the annular walls of the casing whereby to provide mixing chambers, annular flanges at the ends of the respective tubular extensions, said flanges being adapted to engage the inner surface of the wall of the casing whereby to constitute guides for the valve and end closures for the mixing chamber, each of said tubular extensions having a plurality of series of vertically spaced circumferentially disposed narrow slots whereby to permit the material to escape into the

mixing chambers in finely divided particles, a plurality of inlets in the casing leading into the open end of the upper tubular extension, and an independently controlled 5 valve for each of said inlets, said valves being mounted upon the casing.

In testimony whereof, I have hereunto

signed my name in the presence of two subscribing witnesses.

WALTER C. WESTAWAY.
